Primary Examiner — Marianne Pandozzi(74) Attorney, Agent, or Firm — Finnegan, Henderson, Farabow, Garrett & Dunner, LLP(57) CLAIM

The ornamental design for a coffee maker, as shown and described.

DESCRIPTION

FIG. 1 is a top, right, front perspective view of a coffee maker showing my new design.

FIG. 2 is a bottom, right, front perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom view thereof.

The even length broken lines in the drawing depict portions of the coffee maker that form no part of the claimed design.
